J. BURGH.
VALVE MECHANISM FOR INTERNAL COMBUSTION ENGINES.
APPLICATION FILED JAN. 24, 1912.
Patented Aug. 19, 1913.
1,070,583.

UNITED STATES PATENT OFFICE.

JOHN BURGH, OF DENVER, COLORADO.

VALVE MECHANISM FOR INTERNAL-COMBUSTION ENGINES.

1,070,583.

Specification of Letters Patent. Patented Aug. 19, 1913.

Application filed January 24, 1912. Serial No. 673,101.

To all whom it may concern:

Be it known that I, JOHN BURGH, citizen of the United States, residing in the city and county of Denver and State of Colorado, have invented certain new and useful Improvements in Valve Mechanism for Internal-Combustion Engines; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in valve mechanism for internal combustion engines, my object being to provide a construction of this character which is practically noiseless, and which shall at the same time be efficient, and therefore reliable and exceedingly durable in use.

In my improved construction, I employ a valve piece having the shape of the segment 25 of a sphere, the said valve piece being removably mounted in a cavity of corresponding shape. The valve is rotatable, and by virtue of its spherical form, fits closely within its seat regardless of wear.

In order to make the valve practically noiseless, provision is made for reducing friction as far as possible, by separating the valve from the pressure within the cylinder, incident to the use of engines of this character.

Having briefly outlined my improved construction, I will proceed to describe the same in detail, reference being made to the accompanying drawing, in which is illustrated an embodiment thereof.

In this drawing: Figure 1 is a longitudinal section, taken through my valve mechanism, centrally cutting the outer extremity of the engine cylinder. Fig. 2 is a similar section taken at right-angles to Fig. 1, or on the line 2—2, Fig. 1. Fig. 3 is a view partly in end elevation, being a section taken on the line 3—3, Fig. 1, viewed in the direction of the arrow. Fig. 4 is a view of the valve mechanism looking in the direction of arrow 4, Fig. 2, the bottom of the cylinder being removed. Fig. 5 is a detail view in elevation of the valve piece.

The same reference characters indicate the same parts in all the views. 5

Referring first more particularly to Figs. 1 to 5, inclusive, let the numeral 5 designate the cylinder of an internal combustion engine, and 6 the piston therein. To this cylinder is secured by means of bolts 7, a head 8, in which is formed a recess 9, constituting a seat for a valve piece 10, this valve piece, as illustrated in the drawing, being approximately of semi-spherical shape, and provided with a passage 12, adapted to communicate with the cylinder chamber 13 for inlet and exhaust purposes. As the valve is rotated, the passage 12 is adapted to register with an induction port 14, formed in the head 8, and also with an exhaust port 15, formed in the same head. By virtue of this construction, the same passage in the valve piece serves for both the introduction of the explosive mixture to the cylinder, and also for the exhaust of the burnt gases or products of combustion therefrom. As illustrated in the drawing, the valve is so arranged in order to advantageously impart the rotary movement thereto, that its axis does not quite coincide with the axis of the cylinder. This valve piece is provided with a stem 16, projecting through a perforation 17, formed in the cylinder head, and freely rotatable therein. The portion of this stem, however, just beyond the head of the cylinder, is formed polygonal, preferably square in cross section, as shown at 18, this portion of the spindle being equipped with a spiral gear 19, meshing with a similar gear 20, fast on a spindle 21, journaled in a cap 22 secured to the head of the cylinder exteriorly, and forming a sort of housing for the outer extremity of the valve mechanism. This spindle 21, protrudes beyond the cap 22 on both sides, and is adapted to receive a gear 23, arranged to mesh with a pinion 24, fast on the adjacent extremity of a shaft 25, whose opposite extremity is connected with the crank shaft of the engine not shown.

In order to hold the valve piece 10 tightly against its seat, the outer extremity of the stem 20 beyond the part 18 is reduced in size, as shown at 26, and surrounded by a spiral spring 27, whose inner extremity engages the gear 19, while its outer extremity engages a pin 28 passed through the outer end

of the valve stem, and forming a stop for the spring. By virtue of this construction, the spring normally acts to draw the valve piece outwardly, and consequently maintains its spherical surface in contact with the cavity or chamber of the head, in which the valve piece is located.

The gear 19 is provided with an extension sleeve 29, which surrounds the spiral spring 27, and is journaled in an inner cap 30, which is secured to the head 8 by screws 31, or other suitable fastening devices. This inner cap is open on one side, as shown at 32, to expose the gear 19 sufficiently to mesh 15 with the gear 20 on the spindle 21, as heretofore explained.

The head 8 of the cylinder is provided with a passage 33 communicating with the chamber 13 of the cylinder; this passage 33 has a laterally extending portion 34 in which the threaded portion 35 of the spark plug 36 is inserted.

The center of the valve piece is provided with a recess or cavity, 37, forming a part 25 of the passage 12, and through which the explosive mixture is introduced to, and the products of combustion escape from the cylinder chamber. This cavity is open at the bottom of the valve piece, and in it is fitted 30 an expansion ring 38, which is divided, as shown at 39, the said ring being under sufficient tension to maintain its position in the valve piece and rotate therewith. Below this ring, and below the bottom, or inner surface 35 of the valve piece, is located a protecting disk 40, provided at its outer edge with a narrow flange 41, which engages a shoulder 42, formed on the cylinder head and surrounded by a collar 43 integral with such head. By virtue of this flange and the expansion ring, which protrudes slightly inwardly below the inner surface of the valve piece, the disk 40 is separated from the valve piece by a narrow space 44, whereby the rotary movement of the valve is not accompanied by any friction resulting from the contact of its inner surface with a stationary part, the only friction being that incident to the engagement of the narrow inner edge of 45 the spring ring 38, which is in contact with the adjacent surface of the disk 40. This disk is provided with a central opening 45, forming communication between the cylinder chamber and the cavity 37 of the valve piece for both induction and exhaust purposes.

For the purpose of supplying the cylinder with explosive mixture, an induction conduit 46 is threaded into the inlet port 14 of 60 the cylinder head, while the products of combustion escape through the port or passage 15 of the head, the axis of the two ports being 90 degrees apart, considered with reference to the circumference of the rotary 65 valve piece.

From the foregoing description, the use and operation of my improved valve mechanism will be readily understood.

Assuming that the crank shaft not shown, of the engine is in operation, rotary movement will be imparted to the valve piece 10 through the medium of the shaft 25, the gears 24 and 23, the spindle 20 and the spiral gears 16 and 19. As this valve is rotated, the explosive mixture is introduced 70 to the cylinder chamber through the conduit 46, the part 14, the passage 12, its central cavity 37, the opening in the bottom of the valve piece, and the perforation 45 in the disk 40, after which, as the valve continues 75 its rotary movement, the products of combustion are exhausted through the cavity 37 and the passage 12, as will be readily understood.

Attention is called to the fact that the expansion sleeve 38, is held against the disk 40, to prevent the entrance of fluid pressure 80 from the cylinder to the space 44, forming a tight joint.

It should be further stated, that the gearing connection between the shaft 25 and the spindle 21, should be such that the said spindle makes one revolution for every two revolutions of the shaft 25, it being assumed 90 that the shaft 25 makes the same number of 95 revolutions as the crank shaft of the engine, which it is assumed is of the four cycle type.

The valve mechanism outside of the body of the cylinder head may operate in an oil bath. For instance, a cap 22 of the construction shown in Figs. 1 and 2 may be 100 filled with lubricating material, and this material will work down around the stem 16 of the valve piece, and thence to the cavity in which the body of the valve piece operates, thus lubricating the entire valve mechanism.

Having thus described my invention, what I claim, is:

1. The combination with a cylinder having a head equipped with a cavity having the shape of a segment of a sphere, the cylinder head being provided with induction and exhaust ports, of a valve of counter-part shape, located in said cavity, and having a 110 passage constantly in communication with the cylinder chamber, means for rotating the valve, whereby its passage is alternately in communication with the induction and exhaust ports of the cylinder head, a disk applied to the cylinder head, interiorly, and having a perforation in communication with the cavity of the valve, an expansion ring inserted in the inner extremity of the passage in the valve, and in contact with the 115 said disk and surrounding its perforation, the outer edge of the said ring being exposed to the pressure within the cylinder, the disk being separated from the inner face of the valve, substantially as described.

2. The combination with a cylinder having a head equipped with a cavity, of a valve fitting closely in said cavity and rotatable therein, said head having inlet and exhaust ports opening into said cavity, a disk separating said cavity from the cylinder, an opening in said disk, a passage in said valve communicating constantly with said opening and intermittently with said inlet and exhaust ports, said valve being separated from

said disk except for a small cylindrical portion surrounding the opening in said disk, and means for rotating said valve.

In testimony whereof I affix my signature in presence of two witnesses.

JOHN BURGH.
